ROBERT G. REDMANN, OF BRISTOL, CONNECTICUT, ASSIGNOR TO THE SESSIONS FOUND-
DRY COMPANY, OF BRISTOL, CONNECTICUT, A CORPORATION

CAST-IRON INGOT MOLD

Application filed November 15, 1928. Serial No. 319,593.

My invention relates to improvements on cast iron ingot molds of the general form that is shown and described in the application filed by myself September 1, 1928, Serial No. 303,592, and the object of my present improvement is to provide means for connecting the two parts of the mold and for locking the parts in the closed position that will be operatively effective and efficient and that will permit of readily separating and disconnecting the parts.

In the accompanying drawing:—

Figure 1 is a front elevation of a cast iron ingot mold that has the two parts hingedly connected and that is provided with locking means embodying my invention.

Figure 2 is a side elevation of the same.

Figure 3 is a fragmentary view on an enlarged scale of the side of the back part.

Figure 4 is a similar view of the front part.

Figure 5 is a view of the wedge and adjacent parts as viewed from the rear.

Figure 6 is a sectional view on the line 6—6 of Fig. 2, showing dove-tail cross-section of the wedge and the guideways therefor.

Figure 7 is a view corresponding to Fig. 5 with the wedge in a different position.

My improved cast iron ingot mold comprises a back 10 and a front 11 that are hingedly connected by their lower ends by improved means to be described and that are surmounted by a pouring cup or strainer 12 that is hingedly connected to said back 10 in the manner described in the application that is referred to above. Also, the locking means are improved, involving the use of a wedge 13 at each of the different locking points or stations, of which latter there is provided a plurality located at the sides and distributed along the length, the number varying according to the length of the mold.

Both the hinge connection and the locking means permit of readily separating the front from the back bodily.

As to the hinge connection, the front 11 is provided with a pair of lugs 14 that overhang the lower end portion or supporting portion 15 of the back 10 and that are opposed respectively to the adjacent outer faces 16 thereof. Each lug 14 is provided with an inward-

ly projecting hinge or pintle member 17 that cooperates with a suitable recess 18 that is provided in the corresponding outer face 16.

Said recess 18 suggests a modified form of the receiving recess of a bayonet joint, being generally of U-shape, comprising an entrance branch 19 that opens transversely through the face 16; a longitudinally directed connecting passage 20; and a shorter bearing branch that is closed at the end 22 to provide the bearing for the pin or pintle member 17.

The structure described provides a hinge connection that permits of swinging the front to and fro relatively to the back for closing the pouring cavity and opening to remove the casting substantially in the usual manner and permits of bodily separating the front from the back.

The locking means comprise suitable lugs for cooperating with the wedge 13, involving on one of the mold parts an overhanging structure for holding one lug and on the other of the mold parts spaced lugs for admitting said one lug along or through the space therebetween, whereby when the wedge is removed the mold parts can be freely separated.

In the structure that is shown the back 10 carries the overhanging part or wedge hook 23 that supports the single lug 24. The spaced lugs 25 are provided on the front 11 and these are separated by the space 26.

In use, the wedge 13 bridges the space 26 and as it is driven to the holding position serves to lock the back 10 and front 11.

Considering details, the wedge 13 is made of dovetail shape for the cross-section and the ways 27 or contacting faces on the spaced lugs 27 are under-cut to correspond so that there is a tendency to locate the holding strain on the side of the inner corner 28 of the lug. Also, this form serves to keep the wedge from being forced outwardly and separating the wedge from the back 10. Further holding means are provided for the wedge so as to positively retain the wedge at the side of the supporting back 10, comprising an overhanging housing or wedge box 29 on said front 11 and a special shape for the wedge involving lengthwise tapering thereof, and a cooperating shape for the box-way.

Said housing 29 supports a depending plate-like web or rib 30 that is separated from the adjacent side face 31 of the front 11 by a space 32 for admitting the wedge and the inner face 33 of said rib 30 serves as a pressure face for making forcible sliding contact with the outer face of the wedge. Said inner face 33 is suitably inclined and the wedge has either the whole or a portion of the opposed face 34 correspondingly inclined so that when the wedge is lifted beyond the locking position in its engagement with the mold lugs the wedge itself will be held by a wedging effect within the space 32.

15 In other words, the wedge is made wedge-shape for the usual function as a wedge and is also made wedge-shape as to its thickness either for a suitable portion of its length, or such tapering of the wedge may be extended 20 throughout the entire length thereof. Only the thickest part of the wedge functions in holding the wedge in the wedge box, and said thickest part is towards or adjacent the small end 35 of the wedge 13 as to the width, which 25 functions in holding the mold back member 10 and the front member 11 in the locked position.

The strains to which the locking lugs are subjected in casting are relatively enormous 30 and, therefore, I find it desirable to incorporate in the body portion 36 of the wedge hook 23 a reinforcing member 37 of wrought iron rod that is, embedded therein in casting. As shown, said reinforcing member 37 is of U- 35 shape and the ends 38 thereof project beyond the adjacent outside face of the hook body portion 36 and are headed over.

At the end of the wedge 13 remote from the narrow end 35, that is to say, at the head end 40 or the large end there is provided an overhanging lug 39 that serves as a handle or releasing lug that can be struck by a hammer to loosen the locking hold.

The body portion 36 of the hook 23 is outside the lug 24 that is supported thereby. The wedge is positioned between said body portion and the opposed side face of the mold.

I claim as my invention:—

1. In a cast iron ingot mold, a back and 50 a front constructed to meet by their confronting edges and provided with locking means for holding in closed position, said locking means comprising a wedge and integral lugs for cooperating therewith, said lugs comprising a single lug supported by means of an overhanging part on one of the mold parts and a pair of spaced lugs on the other of the mold parts.
2. In a cast iron ingot mold as described 60 in claim 1, said back and front being provided with hinge-connecting means that permit of separation, one from the other, when the mold parts are in the open position, comprising overlapping faces on the opposite sides of the mold parts, one face of each pair

being provided with a circuitous or bayonet-joint slot, and the other face of each pair having a pintle lug that projects into the said slot.

3. In a cast iron ingot mold as described in claim 1, said overhanging part comprising a body portion, and said body portion having a reinforcing structure in the form of a U-shaped rod of wrought iron or the like that is cast therein. 70

4. In a cast iron ingot mold as described in claim 1, said overhanging part comprising a body portion that extends along and across the mold side at the junction of the two mold parts and across the wedge, and said body portion being on the other side of said wedge, 80 the wedge being directly opposed to and in face to face contact with the adjacent portion of the side face of the mold. 75

5. In a cast iron ingot mold, two mold parts, 85 one of said parts having extensions that project outside the other part on the opposite sides, one of said mold parts being provided with circuitous bayonet joint slots, and the other of said parts having pintle lugs that enter said slots for effecting pivotal connection of the mold parts. 90

6. In a cast iron ingot mold, two mold parts that meet along contacting faces, a set of lugs on said parts for cooperating with means for holding the mold parts together, said means being in the form of a wedge that is adapted to be moved to and fro between the locking and unlocking positions, a guide housing on one of said mold parts having faces for cooperating with said wedge, and said wedge having the small end thickened for making frictional engagement with the opposed guide faces for holding the wedge in the position in which the wedge and lugs are unlocked. 95
